PIPE

Peter H. Seckel, Upper Montclair, and Franklin Dick,
New York, N.Y., assignors to Dart Industries, Inc.,
Los Angeles, Calif.

Filed Apr. 30, 1970, Ser. No. 22,728

Term of patent 14 years

Int. Cl. D23—01

U.S. Cl. D23—45

FIG. 1

FIG. 2

FIG. 3

FIG. 6

FIG. 5

FIG. 4

FIG. 1 is a side elevation of a pipe embodying our new design;

FIG. 2 is a cross-section taken on line 2—2 of FIG. 1;

FIG. 3 is a cross section taken on line 3—3 of FIG. 1;

FIG. 4 is a side elevation of a modified form of the pipe shown in FIG. 1, wherein said modification is a reduction in the number of longitudinal ribs;

FIG. 5 is a cross section taken on line 5—5 of FIG. 4; and

FIG. 6 is a side elevation of a second modified form of the pipe shown in FIG. 1.

We claim:

The ornamental design for a pipe, substantially as shown.
